ATTORNEY

UNITED STATES PATENT OFFICE.

JOHN A. HUTCHISON, OF CAMBRIDGE, MASSACHUSETTS, ASSIGNOR TO THE MERRIMAC MATTRESS MANUFACTURING COMPANY, OF BOSTON, MASSACHUSETTS.

DESIGN FOR A MATTRESS-FRAME.

SPECIFICATION forming part of Design No. 80,375, dated March 21, 1899.

Application filed February 17, 1899. Serial No. 705,892. Term of patent 7 years.

To all whom it may concern:

Be it known that I, JOHN A. HUTCHISON, a citizen of the United States of America, residing at Cambridge, in the county of Middlesex and State of Massachusetts, have invented and produced a new and original Design for Mattress-Frames, of which the following is a specification, reference being had to the accompanying drawings, forming a part thereof.

10 Figure 1 shows a perspective view of a mattress-frame of my design. Fig. 2 shows, on an enlarged scale, a plan view of one of the corners of the frame. Fig. 3 shows, on an enlarged scale, a perspective view from the inner side of one of the corners of the frame. Fig. 4 shows, on an enlarged scale as compared with Fig. 1, a perspective view from the outer side of one of the corners of the frame.

15 The feature of the design is the form, shape, and arrangement of the parts constituting

the mattress-frame, as follows: The side rails 1 having upwardly-crooked ends, as shown, and superposed angular cross-bars 2 and braces 3 spanning the corner between the parts 1 and 2 and having the overhanging portion 4, as shown, all arranged substantially as shown. 25

Having described my invention, what I claim as new, and desire to secure by Letters Patent, is—

30 The design for a mattress-frame, substantially as herein shown and described.

In witness whereof I have hereunto affixed my signature, in the presence of two witnesses, this 13th day of February, 1899.

JOHN A. HUTCHISON.

Witnesses:

ALBION L. MILLAN,
